UNITED STATES PATENT OFFICE.

AXEL FRITZ, OF EVERETT, MASSACHUSETTS.

FOLDING GATE.

1,151,518.

Specification of Letters Patent. Patented Aug. 24, 1915.

Application filed October 1, 1914. Serial No. 864,527.

To all whom it may concern:

Be it known that I, AXEL FRITZ, a citizen of the United States, residing at Everett, in the county of Middlesex and State of Massachusetts, have invented new and useful Improvements in Folding Gates, of which the following is a specification.

This invention relates to improvements in folding gates of a type somewhat similar to 10 the type illustrated in my prior application for "folding gates," Ser. No. 848,881, filed July 3, 1914.

The object of this invention is to provide an improved type of guide bar over the 15 form shown in said prior application and also an improved method of supporting the pales of the gate on said guide bar.

Another object of the invention is to provide means for alining and supporting the 20 ends of the guide bars of the gate sections.

Still another object of the invention is to provide improved means for interlocking one section of a gate with another.

The invention consists in the combination 25 and arrangement of parts whereby the above objects and certain other objects hereinafter appearing may be attained, as set forth in the following specification and particularly pointed out in the claims.

Referring to the drawings: Figure 1 is 30 an elevation of one section of a double folding gate embodying my invention with the same shown extended. Fig. 2 is an elevation of the other section of the gate with the 35 same folded. Fig. 3 is a sectional elevation taken on the line 3—3 of Fig. 1. Fig. 4 is a detail underneath plan view of the abutting ends of the guide bars for the gate sections illustrating the means for interlocking 40 the gates when they are in their extended positions. Fig. 5 is a section taken on the line 5—5 of Fig. 4. Fig. 6 is a section taken on the line 6—6 of Fig. 1. Figs. 7 and 8 are detail views of the means for locking 45 the gate sections together. Figs. 9 and 10 are detail views of a section of gate embodying a modified form of my invention.

Like numerals refer to like parts throughout the several views of the drawings.

In the drawings, 12 and 13 represent 50 two coöperating sections of a folding gate each of which consists of a series or plurality of pales 14 arranged substantially parallel to each other and adapted to be moved laterally relatively to each other during the opening and folding of said gate sections.

To guide and support the pales 14 during their lateral movement bars 15 and 16 are provided adjacent their upper and lower ends respectively, said bars being preferably 60 channels and arranged transversely of said pales to slide preferably through U-shaped brackets 17 secured to each of said pales preferably by riveting the ends of said brackets. A roller 18 is journaled to rotate 65 upon one of the arms of each of said U-shaped brackets preferably the upper arm 17' and engages the upper face of said channel bar 15, permitting said pales to easily slide lengthwise of said guide bars. To 70 limit the lateral movements of said pales and properly space the same relatively to each other, a pair of links 19 connect the upper ends of each pair of adjacent pales together, while a second pair of links 20 connect the lower ends of each pair of adjacent 75 pales together. The links constituting said pairs are pivoted together at 21, while the opposite ends of the links constituting said pairs are pivotally connected at 22, 22 to 80 their respective pales, said pivots 22, 22 preferably consisting of the lower arms of the U-shaped bracket 17 which are extended slightly beyond the faces of the pales 14 to receive said links.

The links in the gate illustrated in Figs. 1 and 2 are adapted to swing upwardly to permit the folding of the gate and downwardly during the opening thereof and to prevent said links from moving too far one 85 of the links of said pairs is provided with a projection 23, which extends beyond the pivot 21 and engages the edge of the other link of said pair, thus preventing the straightening of said links which if permitted would cause the pivot 21 to drop below the centers of the pivots 22 of said links and thus move downwardly rather than upwardly when the gate is being folded. The other link of each pair is also extended 90 beyond the pivot 22 at 24 to form a stop which assists the projection 23, which also forms a stop, in limiting the movements of said links.

With the links arranged in the positions 105 just described there will be little or no resistance aside from the friction due to the weight of the several pales, to the folding of said gate, permitting the pales 14 to be moved to contact with the adjacent pales of 110 the series, as will be seen by referring to Fig. 2. To further add to the attractiveness

in the appearance of the gate, a second series of pales 25 have been provided, said pales being arranged upon the opposite face of the series of links connecting the pales 14, and 5 secured to said links by the studs constituting the pivots 21. The pales in said second series are also slightly shorter than the pales 14 so that when the gate is open the lower 10 ends of the pales 25 will aline with the lower ends of the pales 14, but the upper ends of said pales 25 will be slightly below the upper ends of said pales 14, see Fig. 1.

As the gate is folded the pivots 21 are moved upwardly as the pales 14 to which 15 they are secured are moved together, which upward movement carries said pales 25 upwardly relatively to the pales 14 until the upper ends of said pales aline with the upper ends of the other of said series of pales, 20 as will be seen by referring to Fig. 2. By this arrangement it will be seen that the least possible amount of space will be occupied by said pales when the gate is in its folded condition. In both sections of said 25 gate one of the end pales, preferably the pale 26 is pivotally secured to any suitable support and in any desired manner, thus permitting the whole section to swing about the axis of said pale 26. In the present in- 30 stance I have shown the pale 26 pivotally mounted upon a bracket 27 which is secured to the floor 32 of the door or entrance to be closed by said gate, while the upper end of said pale is journaled at 28 in a bracket 29 35 secured to the wall of the opening. The pale 30 at the opposite end of the gate from the pale 26 is provided at its lower end with a supporting roller or caster 31 adapted to roll upon the floor 32 and support the outer 40 ends of the bars 15 and 16. The inner ends of the bars 15 and 16 are secured to the pivoted pale 26 and in this manner the extremities of said bars will be supported and provide suitable supports for the intermediate 45 pales of both series.

In order that the sections of the gate may take up as little amount of space as possible when the gate is folded, the bars 15 and 16 are jointed at one or more places according 50 to the length of the gate. In the present gate however but one joint 33 is necessary, which joint is at such a distance from the pivoted pale 26 that when the pales 14 are moved to their folded position, as shown in 55 Fig. 2, the outer or free end of the bar 15 may be turned downwardly about the axis of its joint 33 and the bar 16 turned upwardly about the axis of its joint 33 to lie along side of each other, as indicated in Fig. 60 2 and in these positions said bars, or at least, the outer joints thereof may be secured or held against the outermost pale 30 of the gate section either by friction, due to the tightness of the joints 33, or by any other 65 suitable means, thus said gate will occupy

but slightly more space than the combined diameters of the pales 14. The outer ends of the guide bars 15 and 16 preferably terminate in alinement with the outer faces of the outermost pales 30, but when the two 70 sections of the gate are brought together in alinement it is important that said bars be retained in alinement to strengthen said gate. For this purpose a sliding bolt 34 is mounted within the groove 35 provided in 75 each of the channels 15 and 16 of one section of the gate, preferably the section 12. A pin 36 is secured in said channels and extends through a slot 37 formed in said bolt permitting a limited sliding movement of 80 said bolt within its channel. When the corresponding guide bars of the two sections of the gate are moved into alinement with each other the bolts 34 are adapted to be moved into the grooves of said corresponding bars 85 and thus positively lock said bars in alinement. The groove 35 in said bars is preferably open at the under side thereof and to support said bolt within said groove, plates 38, 38 are provided adjacent the ends of each 90 of the sections of said bars and upon said plates said bolt is adapted to slide.

When the bolt 34 is not in use it is essential that it be prevented from projecting or extending beyond the end of the guide 95 bar within which it is mounted and for this purpose a plurality of teeth 39 are formed upon the under side thereof and adapted to be engaged by a pawl 40 secured to the plate 38 upon the bar containing said bolt, said 100 pawl having a weight 41 adapted to normally retain the same in contact with said teeth.

To lock the two sections of the gate together when the same are closed I have provided an ornamental plate 42 which is secured to one of the pales 30, preferably of the gate 12, said plate having an eye 43 fast thereon and projecting laterally from the front face thereof. The pale 30 of the other 110 section of gate is provided with a sliding plate 44 which is adapted to be moved through said pale 30 after the same has been moved into contact with the ornamental plate 42, through a slot 45 formed in said 115 ornamental plate parallel with the eye 43. A pin 46 is adapted to engage a slot 47 formed in said sliding plate to limit the sliding movement of said plate in said pale permitting said plate however to be moved outwardly sufficiently to aline with the eye 43, whereby the shackle 48 of a padlock 49 may be inserted through the end of the slot 47 and the eye 43 to secure said pales together. 120

In Figs. 9 and 10 I have shown a section 125 of a modified form of gate, which form consists of a plurality of vertically disposed pales 50 having a guide bar 51 similar in form to those illustrated in Figs. 1 and 2, that is to say, said guide bars are of the 130

channel construction. U-shaped brackets 52, 52 are secured to the upper and lower ends respectively of the pales 50 through which the bars are adapted to slide. A 5 roller 53 is journaled upon the upper arm of the U-shaped bracket 52 and rolls along the upper surface of the guide bar 51, while to the lower arm of each of said brackets directly beneath the guide bar 51 is secured 10 links 54 and 55 which in turn are pivotally connected together intermediate said pales for the purpose of limiting the lateral movement of said pales relatively to each other, as shown in Fig. 9, while Fig. 10 illustrates 15 the gate folded and the links dropped down.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific application herein shown, but 25 that extensive deviations from the illustrated form or embodiment of the invention may be made without departing from the principles thereof.

Having thus described my invention what 30 I claim and desire by Letters Patent to secure is:

1. A folding gate having, in combination, a plurality of pales adapted to be moved laterally relatively to each other during the 35 opening and folding of said gate, a bar arranged transversely of said pales adapted to guide the same during their lateral relative movements, a U-shaped bracket secured to said pales adapted to receive said guide-bar, and a roller journaled to rotate upon one of the arms of said brackets in contact with said bar.

2. A folding gate having, in combination, a plurality of pales adapted to be moved laterally relatively to each other during the 45 opening and folding of said gate, a bar arranged transversely of said pales adapted to guide the same during their lateral relative movements, a U-shaped bracket secured to said pales adapted to receive said guide-bar, and a roller journaled to rotate on the upper arms of said brackets adapted to roll upon the upper surface of said bar.

3. A gate comprising a pair of coöperating folding sections, a series of pales in each of said sections adapted to be moved laterally relatively to each other during the opening and folding of said sections, guide bars arranged transversely of said pales adapted to support and guide the same during said lateral movements, the bar of one of said sections adapted to aline with the bar of the other of said sections, and a bolt slidably arranged adjacent the end of one of said bars adapted to slide into the end of the

other of said bars to lock said bars in alinement with each other.

4. A gate comprising a pair of coöperating folding sections, a series of pales in each of said sections adapted to be moved laterally relatively to each other during the opening and folding of said sections, guide bars arranged transversely of said pales adapted to support and guide the same during said lateral movements, the bar of one of said sections adapted to aline with the bar of the other of said sections, a bolt slidably arranged adjacent the end of one of said bars adapted to slide into the end of the other of said bars to lock said bars in alinement with each other, and means to normally retain said bolt within its supporting bar.

5. A gate comprising a pair of coöperating folding sections, a series of pales in each of said sections adapted to be moved laterally relatively to each other during the opening and folding of said sections, guide bars arranged transversely of said pales adapted to support and guide the same during said lateral movements, the bar of one of said sections adapted to aline with the bar of the other of said sections, a bolt slidably arranged adjacent the end of one of said bars adapted to slide into the end of the other of said bars to lock said bars in alinement with each other, teeth formed upon one face of said bolt, and a pawl on said bar adapted to engage said teeth and normally retain said bolt within its respective bar.

6. A gate comprising a pair of coöperating folding sections, a series of pales in each of said sections adapted to be moved laterally relatively to each other during the opening and folding of said sections, a channel bar arranged transversely of the pales in each of said sections, the bar of one of said sections adapted to aline with the bar of the other of said sections when said gates are closed, a bolt slidably arranged within the groove of one of said channel bars adapted to be moved into the groove of the other of said bars when said bars are in alinement with each other to lock said bars in alinement, teeth formed upon one face of said bolt, and a pawl adapted to engage said teeth and normally retain said bolt within its respective channel bar.

7. A folding gate having, in combination, a series of vertically disposed pales adapted to be moved laterally relatively to each other during the opening and folding of said gate, a guide bar arranged transversely of said pales adapted to support and guide said pales during their lateral movements, a U-shaped member secured to each of said pales adapted to receive said guide bar, a roller journaled to rotate upon the upper arm of said U-shaped member adapted to roll upon the upper face of said guide bar,

- and a series of links pivotally connected to the lower arms of said members adapted to limit the lateral movements of said pales relatively to each other.
- 5 8. A gate comprising a pair of coöperating folding sections, a series of pales in each of said sections adapted to be moved laterally relatively to each other during the opening and folding of said sections, a channel 10 bar arranged transversely of the pales in each of said sections, the bar of one of said sections adapted to aline with the bar of the other of said sections when said gates are closed, a bolt slidably arranged within the 15 groove of one of said channel bars adapted

to be moved into the groove of the other of said bars when said bars are in alinement with each other to lock said bars in said alinement, said bolt having a slot extending longitudinally thereof, and a pin arranged 20 transversely of the channel containing said bolt and adapted to engage the slot in said bolt to limit the sliding movement thereof.

In testimony whereof I have hereunto set my hand in presence of two subscribing witnesses. 25
